UNITED STATES PATENT OFFICE.

WALLACE LIPPINCOTT, OF PHILADELPHIA, PENNSYLVANIA.

BABY-CARRIER.

1,196,003.

Specification of Letters Patent. Patented Aug. 29, 1916.

Application filed August 24, 1915. Serial No. 47,042.

To all whom it may concern:

Be it known that I, WALLACE LIPPINCOTT, a citizen of the United States, residing at Philadelphia, in the county of Philadelphia and State of Pennsylvania, have invented 5 new and useful Improvements in Baby-Carriers, of which the following is a specification.

This invention relates to an improved 10 baby carrier of that type which is adapted for attachment to the person carrying the child.

An object of this invention is to provide 15 a device of this nature which may be suspended entirely from the shoulder; which may be easily and quickly adjusted both to the person and to the child; and which may be made up of flexible material so that it may be easily handled and folded up into 20 relatively small space to be carried in the pocket or hand bag.

Other objects and advantages of this invention will appear from the following detail disclosure of the present embodiment 25 thereof shown in the accompanying drawing wherein—

Figure 1 is a perspective view of the improved baby carrier in carrying position, the child and the person carrying the child 30 being shown in dotted lines in their relative places. Fig. 2 is a plan view of the seat and adjacent parts of the improved carrier.

Referring to the drawing, 10 designates a 35 supporting strap adapted to loop over the shoulder of a person carrying the child, and to extend down against one side and at the front of the person into the natural position usually taken by the arm in supporting 40 the child. The supporting strap 10 is longitudinally adjustable by means of a buckle 11, or a like device to accommodate the carrier to persons of different sizes. The lower end or loop of the strap 10 is provided 45 with a seat 12, the same comprising a separate relatively wide strip secured at its ends to the shoulder strap 10, as shown in Figs. 1 and 2, or comprising a widened integral portion 12^a of the lower end or loop 50 of the strap 10. This seat 12 in both instances is relatively wide so as to provide for a comfortable and substantial support for the child. It is intended that the child sit upon the member 12 in the natural 55 position in which the child is usually carried facing the person to whom the carrier

is adjusted, and to prevent the child from falling backward out of the carrier a back strap 13 is provided. The strap 13 comprises a short length of preferably flexible 60 material secured at its ends to the supporting strap 10 at points spaced a short distance above the respective sides of the seat 12, and is adapted to extend across and support the back of the child when seated. 65

To hold the child from slipping forwardly from the seat 12 between the same and the person upon whom the carrier is adjusted, a retaining strap 14 is secured at its lower end to the forward edge of the seat 12 intermediate the ends thereof. This retaining strap 14 is adapted to pass upwardly between the legs of the child, and is adjustably secured at its upper end, by means of a buckle 15, to a shoulder brace or connecting yoke 16. The 70 yoke 16, as shown, is divided, the portions of which pass over the shoulders of the child from the buckle 15 to the back strap 13, and is secured at its rear end to the intermediate portion of the back strap. It is 75 thus seen that by adjusting the retaining strap 14 through the buckle 15 the retaining strap 14 and the yoke 16 are drawn taut to comfortably fit over a child of any size, and to hold the child from falling or slipping 80 forwardly from the seat.

It is designed to manufacture this baby carrier of flexible washable material, so that the same may be readily cleaned and may be easily folded or rolled into compact form to 90 fit in the pocket, hand bag, or the like, when not in use. In the use of the preferred form shown in the drawings, a single buckle 15 is used for tightening not only the retaining strap 14 and the yoke 16, comprising the 95 upper end thereof, but also for drawing up and holding the back strap 13; thus by one adjustment fitting the entire carrier to the body of the child. The yoke 16 is of sufficient length and size to admit adjustment of the device to children of different sizes. As the retaining strap 14 passes upwardly between the legs of the child, it prevents the child from slipping from the seat when the child stiffens itself or gets too near 100 the edge of the seat.

The device may be first adjusted to the child and then raised into position, when the supporting strap 10 may be thrown over the shoulder and adjusted by means of the 110 buckle 11. Also the shoulder strap 10 may be raised over the head and the child low-

ered before removing the device from the child.

I claim:—

1. In a baby carrier, a supporting strap 5 to be looped over the shoulder of a person and adapted to support the child in its lower end, a back strap secured at its ends to the sides of said supporting strap a short distance above the lower end thereof to engage and support the back of the child and form an open-front seat, a yoke secured to the back strap and adapted to pass over the shoulders and down the front of the child, and means for adjusting said yoke 10 to children of various sizes.

2. In a baby carrier, a supporting strap adapted to be looped over the shoulder of the person carrying the child, and the lower loop of which forms a seat for the child, 20 a back strap secured across the supporting strap above the lower end thereof and adapted to engage and support the back of the child, a retaining strap extending upwardly and forwardly from the lower end of the 25 supporting strap for engagement with the

limbs of the child to prevent the child from slipping from the supporting strap, a yoke secured at one end to the back strap for engagement over the shoulders of the child, and a single adjusting means between the 30 free ends of the yoke and the retaining strap for adjusting the yoke and the retaining and back straps about the body of the child.

3. In a baby carrier, a supporting strap adapted for engagement with the shoulder 35 of the person carrying the child and having a seat portion at its lower end to support the child, straps at the front and rear of the seat portion for engagement about the body of the child, and a single buckle connecting the straps for adjusting the same to children of different sizes.

In testimony whereof I have hereunto set my hand in presence of two subscribing witnesses.

WALLACE LIPPINCOTT.
